Patented Mar. 13, 1900.

E. B. & F. W. MERRIMAN.

KITE.

(Application filed May 3, 1898.)

(No Model.)

UNITED STATES PATENT OFFICE.

EDWARD B. MERRIMAN AND FRANK W. MERRIMAN, OF BOSTON,
MASSACHUSETTS.

KITE.

SPECIFICATION forming part of Letters Patent No. 645,423, dated March 13, 1900.

Application filed May 3, 1898. Serial No. 679,586. (No model.)

To all whom it may concern:

Be it known that we, EDWARD B. MERRIMAN and FRANK W. MERRIMAN, citizens of the United States, residing at Boston, in the county of Suffolk and State of Massachusetts, have invented certain new and useful Improvements in Kites, of which the following is a specification.

Our invention relates to kites, and more particularly to what are known as "box-kites," a type of kite whereof the distinguishing feature is the peculiar arrangement of its sails or aeroplanes, which in their contour resemble two open-ended rectangular boxes rigidly secured together in alignment with each other and a short distance apart.

A box-kite is, as compared to other types, a heavy-wind kite—that is to say, it requires a heavier wind to raise and sustain it—and for this reason it is especially important that it should be as light, strong, and rigid of contour as possible.

Our present invention is intended to improve upon prior box-kites in the particulars just mentioned, and in its preferred form it also provides a kite which may be compactly folded when not in use.

Our invention also relates to an improved device for adjusting the bridle of the kite, as will be hereinafter set forth.

In the accompanying drawings, Figure 1 is a side elevation of a box-kite embodying a preferred form of our improvements, a portion of one of the sails being broken away. Fig. 2 is a top plan view of the kite shown in Fig. 1. Fig. 3 is an enlarged section, partly broken away, on the line $x-x$ in Fig. 2. Fig. 4 is an enlarged view of the bridle-adjuster herein-after described.

Each sail A and B of the kite consists, in accordance with the usual construction, of a strip of cloth or similar material secured to corner-stays 2, which are located at such distances apart that the sails will thereby be given their peculiar box-like contour when extended. Each of said stays is preferably of sufficient length to serve for both sails, thereby also performing the function of spacing said sails apart and uniting them to each other to form the complete kite.

In order to set up the kite, the stays 2 must be held apart and braced in such manner as to stretch the sails taut and maintain them in that condition, and our present invention relates chiefly to the means employed for that purpose. Hitherto it has been customary to provide each pair of stays with one or more braces extending between them adjacent to the corresponding side of the sail, said braces thus forming a rectangle when viewed in plan. According to our invention, however, we brace the stays apart and stretch the sails by means of a suitable number of cross-braces 3, each of which extends between diagonally-opposite stays in a plane substantially at right angles thereto, as clearly shown in Fig. 2, so that the pressure exerted by each brace is directly opposed to the resultant of the tensions exerted on the corresponding corner-stays by the adjacent portions of the sail. From this construction there results, first, a considerable gain in lightness for the reason that two of our cross-braces are the equivalent of four of the parallel braces such as heretofore used, and, second, there is a great gain in strength and rigidity, because in our structure the framework of the sails is, in effect, divided into triangles, while in the old construction the framework consisted of one or more rectangles, and it is a well-known mechanical fact that a triangle having sides of fixed length cannot be distorted or deformed at its angles, while the contrary is true of a rectangle or any other plane figure having more than three sides. Furthermore, in the old construction the braces were subject to lateral pressure from the action of the wind on those portions of the sail with which they are in contact, while our cross-braces are subject to an endwise pressure only, as above stated, and thus may be made of less cross-section than the old form of brace without any corresponding loss in efficiency, thereby still further lessening the weight of the kite.

We prefer to arrange our cross-braces 3 in pairs, as shown in Fig. 1. For the smaller sizes of kite a single pair of braces for each sail will be sufficient, and they should be located about midway between the edges of the

sail, as shown. For the larger sizes of kite two or more pairs of braces for each sail may be used, if desired.

In order that the kite may be conveniently folded when not in use, we prefer to make the braces 3 detachable at one or both of their ends from the stays 2, and this may be done by pivoting one end of each brace 3 to one of its corresponding corner-stays and providing means for its temporary attachment to the diagonally-opposite stay. In the construction shown a tubular clip 4 is secured on one end of each brace 3, ears 5 being provided on said clip by means of which it is pivoted, as at 6, to the corner-stay, which is rectangular in cross-section and is positioned diagonally with reference to the sails, so as to present a flat bearing-surface to the cross-brace. To the free end of each brace 3 a clip 20 or ferrule 7 or its equivalent is secured, it being provided with two ears 8, projecting forward from its sides in such manner that said ears 8 may be made to embrace the corner-stay and slide along the same until the 25 brace is in its operative position, which may be determined by means of a stop 9, secured to the corner-stay. It will be obvious that by means of the construction just described a very considerable amount of force may be 30 applied to the corner-stays 2 in bracing them apart, thereby giving a corresponding tension to the sails, and thus increasing the rigidity of the kite.

The clips 7 are preferably made of metal, 35 and in order that the ears 8 may have sufficient strength without being made unduly heavy they may be corrugated longitudinally, as at 14. If the two cross-braces of each pair are pivoted together at their point of crossing, as at 10, the rigidity of the kite will be somewhat increased, while the folding of the kite will not be interfered with thereby.

The bridle of the kite—*i. e.*, the two cords 11, which are to be attached to the kite-line—45 is secured to the kite-frame at or near the inner edge of one of the sails, one cord on each side. The points at which the bridle should be secured to the kite-frame in order to secure a proper balance of the kite when 50 in the air vary according to the strength of the wind, being nearer the end of the frame when the wind is strong than when it is light. The remaining feature of our invention relates to means for adjusting the bridle on the 55 kite-frame and consists of a wire or its equivalent secured to the frame of the kite at about

the proper point of attachment for the bridle and so constructed that the bridle may be conveniently adjusted along said wire a predetermined distance and retained in place 60 until it is desired to change its position. The simplest form of this feature of our invention which has occurred to us is that shown in detail in Fig. 4 of the drawings, wherein 12 is a piece of stiff wire formed into a series of 65 similar wave-like portions or corrugations 13, the ends of the wire being so bent that they may be driven into or otherwise secured to the framework of the kite. Two of these adjusters 12 are of course provided for each kite 70 and the respective ends of the bridle are knotted thereto somewhat loosely, so that the knot may be slipped along the wire into any one of the corrugations 13, which are of such depth that the knots cannot be accidentally 75 displaced therefrom during the flying of the kite. The two ends of the bridle should be adjusted to the same distance from the edge of the sail and this is accomplished very easily by means of our adjuster by simply counting the number of corrugations over which the knots have been slipped.

Our bridle-adjuster may be used with advantage on kites other than box-kites, as will be obvious.

85

We claim as our invention—

1. A knockdown box-kite comprising in combination four corner-stays having sails secured thereto, and two or more pairs of intersecting, diagonal braces each pivoted at 90 one end only to one of said stays and provided at its free end with a U-shaped clip for detachably engaging the opposite stay, each pair of said braces being pivoted together at the point of their intersection, for the purpose set forth.

2. In a kite, a bridle-adjuster comprising a wire secured to the kite-frame and provided with means for retaining the bridle at predetermined points along its length.

100

3. In a kite, a bridle-adjuster comprising a wire adapted to be secured at its ends to the kite-frame, and bent to form a series of corrugations, for the purpose set forth.

In testimony whereof we have hereunto subscribed our names this 29th day of April, A. D. 1898.

EDWARD B. MERRIMAN.
